UNITED STATES PATENT OFFICE

CHARLES W. LUMMIS, OF WORCESTER, MASSACHUSETTS.

INGOT-MOLD.

1,192,919.

Specification of Letters Patent. Patented Aug. 1, 1916.

Application filed September 9, 1913. Serial No. 788,882.

To all whom it may concern:

Be it known that I, CHARLES W. LUMMIS, a citizen of the United States, residing at Worcester, in the county of Worcester and

5 Commonwealth of Massachusetts, have invented a new and useful Improvement in Ingot-Molds, of which the following, together with the accompanying drawing, is a specification.

10 My invention relates to ingot molds and more particularly to an improved form of mold which permits a plurality of metal ingots to be poured simultaneously.

In the metal sheet, wire and tube industry, it is customary to cast brass and similar alloys into bars or rods of comparatively small cross section and to roll or draw these bars or rods while cold to the desired sizes. The castings or ingots are usually made one

20 at a time in metal molds, the molds being formed of plates held together by bands and wedges which are removed after the castings have set to allow them to be taken out of the molds. In some cases permanent 25 molds have been used, the bottoms of these permanent molds being provided with plugged openings so that, after the castings have set, the plugs may be removed and the castings pushed out through the tops of the molds. This is an undesirable construction as it is difficult to make the plugs fit properly, the result being that fins are formed on the bottoms of the castings so as to cause them to bind in the molds and make

30 them difficult to remove. It is desirable to pour the castings or ingots in permanent molds in order to save the labor of dismantling and reassembling the molds after each pouring.

40 One object of this invention, therefore, is to provide a permanent ingot mold so constructed that the ingots may be removed therefrom without opening or dismantling any part of the mold.

45 In order to save time, labor and space, it is also desirable to pour a plurality of the ingots simultaneously, and another object of the invention is to provide an improved form of ingot mold which will permit this 50 to be done. The form of mold to be described hereafter as illustrating the invention is designed for the simultaneous pouring of two ingots; it is apparent, however,

that by increasing the number of ingot cavities in the mold, the number of ingots which may be poured simultaneously will be correspondingly increased.

Other objects and advantages will appear from the following description taken in connection with the accompanying drawing, in which—

Figure 1 is an elevation of an ingot mold with its strainer constructed in accordance with my invention; Fig. 2 is a plan view of the mold and strainer shown in Fig. 1; Fig. 3 is a vertical sectional view on the line 3—3 of Fig. 2; Fig. 4 is a vertical sectional view of the strainer and the upper extremity of the mold on the line 4—4 of Fig. 2; and Fig. 5 is a horizontal sectional view on the line 5—5 of Fig. 1.

Like reference characters refer to similar parts in the different figures.

In the form of invention shown in the drawing, the mold includes three sections or plates 1, 2 and 3, the sections being recessed to form two cavities 4 and 5. The outer sections 1 and 3 are provided along their edges with apertured lugs 6 through which bolts 7 are passed to bind the sections together. A bottom plate 8 is fastened against the lower ends of the sections 1, 2 and 3 by screws 9, this bottom plate serving to close the lower ends of the cavities 4 and 5. Strengthening ribs 10 are formed on the outer faces of the outer sections 1 and 2.

A strainer 11 rests upon the top of the sections 1, 2 and 3 of the mold for the purpose of directing the molten metal into the cavities 4 and 5. The lower edges of the side walls of the strainer fit closely against the tops of the sections 1, 2 and 3 and the walls are solid or imperforate to obstruct the escape of molten metal over the outer edges of the mold and away from the ingot cavities except for a plurality of small openings 12 formed through the walls a short distance above their lower edges. A horizontal shelf 13, just above the openings 12, has a number of openings 14 located above the cavities 4 and 5 for directing the molten metal into these cavities. Pins 15 serve to position the strainer properly upon the sections 1, 2 and 3 of the mold.

The ingots 16 are formed by pouring molten metal into the strainer 11, the metal flow-

ing through the openings 14 in the shelf 13 and thence into the cavities 4 and 5 where it cools and hardens into the shape determined by these cavities. One of the cavities is liable to fill more rapidly than the other and, when this happens and one of the cavities is filled before the other, metal which would otherwise flow into the full cavity then flows over the top of the central section or partition 2 into the other cavity until this also is full. During the filling of the mold, the openings 12 in the side walls of the strainer permit the escape of gases from the mold and also allow molten metal to escape if the mold is filled too full. The lower portions of the side walls of the strainer, being solid below the openings 12 and fitting closely against the top of the mold, prevent molten metal from above that cavity which fills first from escaping and compel it to flow over into the other cavity. This construction permits a plurality of ingots to be poured simultaneously without watching carefully to see which ingot cavity is filled first.

Another advantage of the solid lower edges of the strainer is that a sufficient quantity of molten metal may be supplied not only to fill the cavities 4 and 5, but also to rise somewhat above the central section or partition 2. This extra metal above the top of the section 2 serves as a shrink head 17 to feed molten metal into the tops of the ingot cavities as the metal cools and shrinks, thus preventing the formation of shrink holes and pipes. After the molten metal has cooled and hardened or set, the strainer is removed, leaving the shrink head 17 projecting above the mold so as to serve as a hold for stripping tongs for pulling the ingots from the mold. This does away with the necessity of opening the bottom of the mold or dismantling the mold in any way. After the molten metal has been poured into the ingot cavities, the lower or inner ends of the ingots cool and harden or set before other portions thereof because the radiation of heat is greatest at these points, the inner ends fitting the ingot cavities rather tightly after they have hardened. The intermediate portions of the ingots, however, cool more slowly and, therefore, are more contracted in cross section than the inner ends. These intermediate portions, therefore, after hardening fit loosely within the ingot cavities. The lower ends of the ingot cavities are somewhat contracted as shown in Fig. 3 so that, after the ingots have been started a short distance from the mold, the contracted inner or lower ends of the ingots will no longer fit tightly against the walls of the cavities and the whole of each ingot may be easily withdrawn from the mold. It is well known that ingot molds have been made with contracted end portions for the pur-

pose of forming ingots with correspondingly contracted ends so that they may be started more easily between the rolls used in rolling the ingots into bars or rods. Such molds, however, have been temporary molds and have been taken apart to allow the ingots to be removed. In accordance with the present invention, a permanent mold is produced which not only forms the ingots with contracted ends so as to allow them to be started more easily between a set of rolls, but which also facilitates the removal of the ingots from the molds without taking the molds apart.

While I have shown and described the details of one form of my invention, I do not wish to be limited to such details, as changes may be made without departing from the spirit of the invention; but having described my invention, what I claim as new and desire to secure by Letters Patent is:

1. The combination, with an ingot mold providing a plurality of ingot cavities, of a metal delivering member common to all of said cavities, said member providing a depending wall inclosing a space with which all of said cavities are in direct communication whereby a shrink head common to all of the ingots is formed during the pouring operation.

2. The combination, with an ingot mold providing a plurality of ingot cavities, of a removable metal delivering member common to all of said cavities, said member inclosing a space with which all of said cavities are in direct communication whereby the overflow from said cavities is confined, to provide a hold for pulling the ingots from the cavities.

3. The combination with an ingot mold providing a plurality of ingot cavities, of means for confining the overflow of metal from said cavities, said means being removable, to permit the simultaneous withdrawal of said ingots by the hold provided by said overflow.

4. An ingot mold having a pair of ingot cavities, and a strainer having side walls to surround the openings of the cavities to obstruct the flow of molten metal from the cavities, the strainer having also a perforated shelf above the partition between the cavities, and one of the side walls of the strainer being perforated above the lowest point of the top edge of the partition to allow excess metal to escape.

5. The combination, with an ingot mold providing a pair of ingot cavities separated by a partition, of a removable metal delivering member common to both cavities, said member having a perforated shelf spaced above the partition, and having a flange depending from said shelf and inclosing a space into which both of said cavities open.

6. An ingot mold providing a plurality of cavities, and a removable member inclosing

a space common to the upper ends of all of said cavities, whereby the overflow therefrom may be rendered available as a hold for withdrawing the ingots from the cavities.

7. The combination with an ingot mold providing a plurality of ingot cavities, of a metal delivering member spaced above and common to all of said cavities, and means interposed between said member and the tops of said cavities for confining the overflow metal therefrom.

8. An ingot mold providing a plurality of permanent ingot cavities, and removable means surrounding the receiving ends of said cavities for confining the overflow metal therefrom, whereby said overflow provides a hold for pulling said ingots from the cavities.

9. An ingot mold providing a plurality of permanent ingot cavities having contracted lower ends, and removable means surrounding the upper ends of said cavities for forming

ing a hold by which the ingots may be withdrawn simultaneously from said cavities. 25

10. An ingot mold providing a plurality of permanent ingot cavities, a chamber common to the upper end of all of said cavities in which the overflow metal therefrom is confined, and removable means adapted to expose the metal constituting such overflow, whereby the latter is rendered available as a hold for simultaneously withdrawing all the ingots from said cavities. 30

11. The combination with an ingot mold providing a plurality of ingot cavities, of a metal delivering member spaced above and common to all of said cavities, having delivery openings directly above each cavity, and means interposed between said member and the tops of said cavities for confining the overflow metal therefrom. 35
